UNITED STATES PATENT OFFICE.

JOHN M. BRADLEY AND CHARLES F. PIKE, OF PHILADELPHIA, PENNSYLVANIA,
ASSIGNORS TO THE SAFETY EYEGLASS COMPANY, OF WILMINGTON, DELA-
WARE, A CORPORATION OF DELAWARE.

EYEGLASS-CASE.

1,328,645.

Specification of Letters Patent. Patented Jan. 20, 1920.

Application filed April 13, 1918. Serial No. 228,453.

To all whom it may concern:

Be it known that we, JOHN M. BRADLEY and CHARLES F. PIKE, citizens of the United States, residing at Philadelphia, in the 5 county of Philadelphia and State of Pennsylvania, have invented certain new and useful Improvements in Eyeglass-Cases, of which the following is a specification.

This invention relates to eyeglass cases 10 and has for its object to obviate and overcome the disadvantages and inconveniences attendant upon the use of the cases now in use owing to their overweight and bulk, and to construct eyeglass cases of a weight as 15 light as possible with due regard to safety and efficiency.

A secondary object in so constructing eyeglass cases is to permit of their being made of precious metals or other valuable materials without unduly increasing the cost or 20 sacrificing their utility.

With these objects in view, the invention consists in the improved construction, arrangement and combination of parts comprising an eyeglass case, hereinafter fully 25 described and afterward specifically claimed.

In order that the construction and operation thereof may be readily comprehended, we have illustrated an improved embodiment of our invention in the accompanying drawings, and will now proceed to fully describe the invention, having reference to said drawings, in which—

Figure 1 represents the invention in front 30 elevation;

Fig. 2, a plan view of the same;

Fig. 3, a view in side elevation;

Fig. 4, a view in rear elevation, and

Fig. 5, a plan view of the construction 40 shown in Fig. 4.

Like reference characters indicate the same parts wherever they occur in any of the figures of the drawings.

Referring specifically to the drawing, 45 indicates the main body or support of the case which consists preferably of a sheet of thin suitable material, such as sheet metal, skeletonized by the removal of any suitable portion of its interior, such as at 7 50 to lighten its weight and at the same time retain sufficient strength and stiffness for all

practical purposes, and this body and all other parts may be plain surfaced or ornamented in any desired manner.

At its upper edge, at about its center laterally, is a hook 8 of an elastic material, to engage in a pocket, button-hole or other opening, to support the case on a garment and at its lower end, preferably centrally, projects an extension 9 which carries at its lower end a reel 10 of any suitable construction and secured by any suitable means such as a screw 11, the reel being provided with a push button 12 to release, in a well known manner, a chain passing through a slot 13 65 in the reel casing and attached to an eyeglass, as at 14, composed of the usual lenses and the bow, as at 15.

At the upper and lower ends of the body or support 6 are provided lateral supports 70 to prevent lateral movement or displacement of the glasses, each comprising a sheet 16 of metal or other suitable material, at substantially right angle to the body provided with a slot 17 parallel with and at a short 75 distance from the body, in which slots the eyeglasses rest and are supported from the body, being drawn therefrom when in use, in a well known manner, the usual spring in the reel winding up the chain and drawing 80 the glasses into the slots when not in use.

In the modification of Figs. 4 and 5 the lateral supports 16^a each comprises a part located transversely to the body and having at each side of the body a rearwardly bent 85 curved hook between which the glasses may be held against lateral displacement, the transverse parts and hooks, or the hooks alone, being formed integral with the body, 90 as may be desired.

The body and other exposed parts of the device, may be made of material to suit the garment upon which they may be worn, and by reason of its construction as described, the cost may be so limited as to permit of 95 the purchase of a case to suit the garment upon which it is to be worn.

Having thus fully described our invention, what we claim as new and desire to secure by Letters Patent of the United States 100 is:—

An eyeglass case comprising a body or

support consisting of a skeleton sheet of suitable material provided with a curved hook of elastic material to engage in a pocket or other opening in a garment, and carrying at its lower end a reel having a chain for attachment to the eyeglasses, a suitable support being provided to prevent lateral displacement, comprising a sheet of

material at substantially a right angle to the body having a slot parallel with and at a short distance from the body.

In testimony whereof we affix our signatures.

JOHN M. BRADLEY.
CHARLES F. PIKE.
